CASH REGISTER, BOOKKEEPING, AND
CALCULATING MACHINEKarl Matts Vigborg, Stockholm, Sweden, assignor
to Kooperativa Förbundet Förening U. P. A.,
Stockholm, SwedenApplication September 25, 1939, Serial No. 296,379
In Sweden August 31, 1938

2 Claims. (Cl. 235—27)

The present invention relates to a device in cash registers, bookkeeping and calculating machines of the kind provided with amount or figure key banks and one or more salesmen's or transaction key bank. One object of the invention is to produce a simple and reliable device for locking by means of a removable key the depressable keys of each salesman's or transaction key bank.

Another object is, in a device of this kind, to provide means for preventing locking of the keys of a key bank, as long as any key in said bank is depressed.

Still another object is to produce a cash register of this type in which the key bank locks and the zeroizing lock are arranged for selective operation, so that the zeroizing mechanism can function only when the key banks are locked and vice versa.

One embodiment of the invention is illustrated 20 on the accompanying drawings, in which

Fig. 1 is a front view and

Fig. 2 is a side view of a device according to the invention.

Figures 3, 4 and 5 show details of the device 25 assuming various positions and

Figures 6 and 7 show on a larger scale sections on the lines VI—VI and VII—VII in Figures 3 and 4 respectively.

Figure 8 is a detail view of the interlock slide. 30

On the drawings the salesmen's or transaction key bank 1 is provided with eight keys 2 divided into two groups, the keys of the group 3A being intended for actuation by one salesman and the keys of the group 3B for actuation by another 35 salesman. In order to give each salesman a possibility of locking his keys, i. e. to prevent a depression of the same, it has been arranged as follows:

Along each of the key groups 3A, 3B there 40 extends a plate 4, one edge of which is turnable around a shaft 5 mounted in the key bank (Figures 6 and 7). The free edge of the plate 4 may thus be rocked away from and towards the respective key shanks, the latter being provided with pins or projections 6. These pins are adapted to cooperate with the free edge of the plate 4, when the same assumes its position shown in Figure 6 i. e. rocked towards the key shanks, and to prevent a depression of the keys. 45 To enable a locking of the plate 4 in this key locking position there is formed a projection 7 on the plate, which projection enters a slot 9 in a member 8. The latter is provided with a notch 10 entered by a pin 11, which is fixed to a plate 55

12 rigidly united with the frame of the machine, said member strives through the action of a spring 14 extending between said pin 11 and a pin 13 on the member to assume the position shown in Figures 3 and 6. In the plate 12 there are further secured cylinder or Yale locks 15. To the inner ends of the locking cylinders 16 there are fixed pins or projections 17. When the members 8 and the locking cylinders 16 assume their positions shown in Figures 3 and 6, in which positions the keys cooperating with the locks can be removed, each of the pins 17 rests against one edge 18 of a recess 19 made in the respective member. A rocking outwards of the respective plate 4 is thus impossible, unless the respective locking cylinder 16 is brought out of locking position.

When this is to take place the locking cylinder 16 is rotated in the direction indicated by an arrow in Figure 3. The pin 17 will now cooperate with the edge 20 of the recess 19, said edge serving as cam or guide surface, the respective member being thereby against the action of the spring 14 displaced in the direction indicated by an arrow in Figure 6. At the displacement of the member 8 the corresponding plate 4 will also perform a rocking movement away from the key shanks and finally reach the inactive position shown in Figures 4 and 7. In this position the pin 17 on the locking cylinder will prevent the member 8 from being returned to the initial position by the spring 14. The keys may now, without being prevented by the rail 4, be depressed, and Figure 7 shows how the pin 6 of a depressed key has passed the free edge of the plate 4. The retaining of the keys in the depressed position is provided for by the common locking rail 22, only visible in Figures 6 and 7.

In order that a salesman shall not be able to lock his keys before all keys have resumed their inactive initial positions the member 8 has a striking surface 21, positioned relatively to the turning centre 16 of the locking cylinder in such a way that the pin 17, as is shown in Figure 5, strikes against said surface before the locking cylinder has reached the position that allows removal of the key. In this position the spring 14 is prevented from returning the member 8 and the plate 4 to their initial positions, since the plate 4 abuts against the pin 6 of the depressed key 2, as indicated with dot-dashed lines in Figure 7.

In the embodiment shown on the drawings there is between the two locks serving for locking the salesmen's or transaction keys a third

lock 23, by means of which a member 24 united with the zeroizing device of the machine may be actuated. Since, for several reasons, the salesmen's or transaction keys should be locked during the zeroizing, said device is constructed in such a way that it is impossible to insert a key into the lock 23 before the keys have been removed from the locks 15, i. e. before the keys 2 have been locked. For this purpose there is provided a slide 25 behind the locks 15 and the lock 23. This slide is provided with a guide slot 26 and three semicircular openings 27, 28 and 29 (Figure 8), said openings being positioned in such a way that, when the slide assumes the position shown in Figure 1, the keys corresponding to the locks 15 may be inserted far enough to enable a turning of the locking cylinders. The inner end portions of the keys then enter the recesses 27, 29 of the rail 25, the shape of said recesses allowing a turning of the respective keys. The recess 28, on the other hand, is, when the slide 25 assumes the position shown in Figure 1, located beneath the key-hole of the lock 23. The key to said lock cannot, therefore, be inserted far enough to enable a turning of the locking cylinder. Thus, no zeroizing can be effected when the portions assume the positions shown in Figure 1.

If, however, the keys are removed from the locks 15, it will be possible to move the slide 25 from the position shown in Figure 1 and upwards until the guide pin 30 in the guide slot 26 strikes against one end of said guide slot. The slide then assumes such position that the recess 28 allows an insertion of the key into the lock 23 far enough to allow a turning of the locking cylinder. When the slide 25 assumes this position it is, however, impossible to insert any of the keys of the locks 15 to the necessary extent.

In order to prevent a zeroizing of the totalizers of the machine, unless the person performing said operation has first made it possible to observe the totalizer or totalizers, the slide 25 is provided with a projection 31 serving as a finger grip. Said projection 31 is of such shape that, when the slide 25 assumes the position shown in Figures 1 and 2, the projection will be located between the edges that are formed by a stationary portion 32 of the casing of the machine and a cover 33 covering the totalizer or totalizers, said cover being preferably hinged and lockable. The slide 25 cannot, consequently, be displaced from its position shown in Figures 1 and 2 until the cover 33 has been opened and the totalizer or totalizers have been made visible.

As will be clear from the above the invention does not only offer a simply constructed, space saving and reliable locking device for the salesmen's or the transaction keys, but the present device prevents also such false and injurious operations as are caused in earlier machines, often only due to lacking attention, in which machines there is no mechanical devices at all for preventing such false operations. Especially in cash registers that are used by several salesmen it is of special importance that one salesman shall not

be able to enter amounts on another salesman's keys. It is, however, of no less importance that the salesmen shall not be able to lock their keys until all keys have returned to their inactive positions and that the person performing the zeroizing shall not have any possibility of actuating the salesmen's or the transaction keys.

Several embodiments are, of course, possible within the scope of the invention and the device may advantageously be modified in order to correspond to various demands in various machines without giving up the idea upon which the invention is based.

Having now described my invention, what I claim as new and desire to secure by Letters Patent is:

1. In a cash register including at least one salesmen's or transaction key bank having a plurality of depressible keys, a rockable member hinged on an axis parallel to said key bank, said member having an edge portion extending along said key bank and being rockable into and out of the path of a portion of each key in said key bank, resilient means urging said member into a key locking position in which its edge projects into the path of said key portions, a locking device to be operated by a removable key, and a reciprocable link connected with said member and positively cooperating with a movable portion of said locking device to rock said member into a position in which said keys are freed for depression when said locking device is unlocked and to prevent locking of said locking device when said rockable member is not in its key locking position, each key including a portion disposed in the path of a portion of said rockable member when said key is depressed, whereby said rockable member cannot be restored to its key locking position and said locking device cannot be locked as long as any key in said key bank is depressed.

2. In a cash register including at least one salesmen's or transaction key bank having a plurality of depressible keys, an elongated plate rockable about an axis parallel to its longitudinal edges and to said key bank into and out of a key locking position, resilient means urging said plate into its key locking position, each key having a shank carrying a projection adapted to cooperate with a longitudinal edge of said plate to prevent depression of the key when said plate is in its key locking position and with one of the plate surfaces when an effort is made to return the plate to its key locking position while said key is depressed, a locking device to be operated by a removable key, and a reciprocable link connected with said member and positively cooperating with a movable portion of said locking device to rock said plate into a position in which said keys are freed for depression when said locking device is unlocked and to prevent locking of said locking device when said plate is not in its key locking position, whereby said locking device cannot be locked as long as any key in said key bank is depressed.

KARL MATTS VIGBORG.
